US00D717381S

(12) **United States Design Patent**
Orenstein et al.

(10) **Patent No.:** **US D717,381 S**
(45) **Date of Patent:** **** Nov. 11, 2014**

(54) **AEROBIC STEP**

(71) Applicant: **The Prophet Corporation**, Owatonna, MN (US)

(72) Inventors: **Amber Orenstein**, Prior Lake, MN (US); **Ben Ton**, South El Monte, CA (US); **Nicole Lee Vanlaanen**, Minneapolis, MN (US); **Louis Frederick Polk, III**, Excelsior, MN (US)

(73) Assignee: **The Prophet Corporation**, Owatonna, MN (US)

(**) Term: **14 Years**

(21) Appl. No.: **29/447,718**

(22) Filed: **Mar. 6, 2013**

(57) **CLAIM**

The ornamental design for an aerobic step, as shown and described.

DESCRIPTION

FIG. 1 is a top perspective view of an aerobic step showing our new design;

FIG. 2 is a top view of the aerobic step of FIG. 1;

FIG. 3 is a first side view of the aerobic step of FIG. 1, the opposite side view being identical;

FIG. 4 is a second side view of the aerobic step of FIG. 1, the opposite side view being identical; and,

FIG. 5 is a bottom view of the aerobic step of FIG. 1.

The broken lines in FIGS. 1-5 show portions of the aerobic step which form no part of the claimed design.

1 Claim, 4 Drawing Sheets
